UNITED STATES PATENT OFFICE.

SALUSTIO VALDÉS CORTÉS, OF VALPARAISO, CHILE.

METHOD FOR PROPULSION OF SHIPS, BOATS, AND FLYING-MACHINES.

1,360,182.

Specification of Letters Patent.

Patented Nov. 23, 1920.

Application filed October 15, 1918. Serial No. 258,170.

To all whom it may concern:

Be it known that I, SALUSTIO VALDÉS CORRÉS, a citizen of the République of Chile, and a resident of the city of Valparaiso, at 5 Number 268 Avenida del Brazil, Chile, have invented certain new and useful Improvements in the Methods for Propulsion of Ships, Boats, and Flying-Machines, of which the following is a specification.

10 My invention relates to propulsion mechanism of the rotating blade or paddle wheel type, mounted on a vertical, horizontal or inclined shaft, at the sides, bottom, bow or stern of a vessel.
15 Hitherto such propeller wheels provided with two or more blades have been arranged to rotate wholly immersed in the medium in which they are employed, air or water, within an impermeable circular hood or casing, 20 known as a paddle box, which covers or screens one half or more of the surface of revolution described by the edges of the rotating blades. The hoods or casings were adapted for concentric movement around 25 the paddle wheel in order to permit a control of the direction of propulsive effort.

The object of my invention consists essentially in new and useful improvements in the structure of the hood or casing, which as 30 in former inventions is completely submerged, and covers approximately one half or more of the paddle wheel, but which I construct with permeable or perforated lateral sides and with holes or openings and 35 deflecting plates or vanes in its periphery, whereby I obtain a greater efficiency of propulsion than has previously been attained with submerged paddle wheels and boxes, together with a lifting or sustaining effort 40 which is especially useful when my system of propulsion is mounted on submarine vessels or airships and aeroplanes.

Constructed in this manner, the action of my improved propelling mechanism may be 45 said to be a combination of the paddle wheel and the turbine, thus characterizing and distinguishing it from all previous inventions. When it is applied to submarine and air vessels, it has certain important advantages 50 which are especially notable in the case of air vessels of the "heavier than air" type, which require a maximum of lifting or sustaining power to be communicated from 55 their engines. These advantages may be stated as follows:

(1) Great lifting power, permitting the

vessel to rise quickly within a short space or run,

(2) Possibility of varying the velocity of the vessel without varying the speed of the 60 engines,

(3) Possibility of stopping the forward movement of the vessel and hovering over a given spot, and

(4) Possibility of descending gradually 65 and in a vertical line.

This ascensional or lifting power of my improved propelling system has its application in submarine vessels, wherein its use constitutes a powerful aid in rising to the 70 surface in case of accident.

The general arrangement of my mechanism consists as in former inventions, of a paddle wheel which may be installed in any suitable part of a vessel with a vertical, 75 horizontal or inclined shaft, conveniently connected to a power source; and a paddle box or casing which covers approximately one half or more of the paddle wheel, and which may be fixed to or built in the body 80 or hull of a vessel or airship, or it can be made movable about its axis by means of any suitable mechanism with the object of permitting a control of the direction of the propulsive or lifting effort of the paddle 85 wheel blades.

Permeable casing or paddle box.—The casing as I have already stated constitutes the essential feature of my invention. It must be constructed with permeable lateral sides 90 and with perforations or with openings and deflecting plates or vanes in its periphery, so that the element in which the propeller rotates has free access in and out of the holes or openings both in the sides and periphery. 95 The deflecting vanes may be fixed or movable.

This new and special form of construction of the paddle box has for its objects, (1) the reduction to a minimum of the friction losses against the insides of the casing, 100 and (2) the utilization of the centrifugal force of the revolving medium, air or water, confined in the casing by converting it into propulsive or lifting effort.

Figures 1 and 2 are respectively vertical sectional and side elevations of one form of the invention.

Figs. 3 and 4 are respectively side and sectional views of another form.

Fig. 5 is a horizontal section of another modification.

105

100

110

Figs. 6 and 7 are side and front elevations of the permeable casing of Fig. 5.

Figs. 8 and 9 are side and sectional views respectively of another modification.

5 Figs. 10 and 11 are side and front elevations of modified forms of permeable casings.

Fig. 12 is a diagram indicating the application of my improvement to an aeroplane.

10 Fig. 13 is a side elevation of another form including manual means for adjusting the vanes.

Fig. 14 is a side elevation of a windmill with my improvement attached.

15 Figs. 15 and 16 are respectively transverse and longitudinal sections of another modification.

Figs. 17 and 18 are respectively front and longitudinal sections of a further modification.

20 Figs. 19 and 20 are respectively side and transverse sectional views of a further modification.

Figs. 21 and 22 are respectively side and plane views of a still further modification.

Figs. 23 and 24 are cross section and side elevation respectively of marine vessels equipped with my improvements.

25 Figs. 25 and 26 are views corresponding to Figs. 23 and 24 respectively but showing a different arrangement of the propelling devices.

30 Figs. 27 and 28 correspond respectively to Figs. 23 and 24, but indicating still further variations of the application of my improvement.

Fig. 29 is a diagram of the side of a submarine body indicating my improvement arranged to lift the vessel.

35 Figs. 30 and 31 are respectively a cross section and a side elevation of a vessel in which the power devices have their shafts arranged perpendicular to the vertical plane of the vessel.

40 Figs. 32 and 33 are respectively a plan view and side elevation of an aeroplane having two propellers arranged thereon.

Fig. 34 is a side elevation of a hydroplane with my improvement thereon.

45 Figs. 35 and 36 are respectively side and front elevations of a windmill with my improvement thereon.

50 As is shown in Fig. 1, which represents a sectional front elevation of the paddle 1 and its casing 2, the water or air has free access in and out of the holes 3 in the lateral sides 4 of the casing. In this way the friction of the moving mass of water or air on the inside walls 5 of the casing is seen to 55 be materially reduced, as it is practically that of water against water, or air against air, whereas with impermeable paddle boxes as used in former inventions, the friction losses were of considerable importance.

60 Fig. 2 represents a side view of a paddle

wheel 1 with its casing 2, showing the holes or perforations 3 in the lateral sides, and the openings 9 in the periphery 10, together with the deflecting plates or vanes 11. It will immediately be seen from Fig. 2 how the centrifugal force of the revolving medium inside the paddle box is utilized as in a turbine, and converted into lifting and propulsive effort. In fact, thrusts in three main directions are obtained, (1) a 70 lifting thrust "A," (2) a propulsive thrust "B," both of which are produced by the rotating blades, while (3) is a combined lifting and propulsive thrust "C" which is converted from the centrifugal force by the 75 impingement and deflection of the revolving water or air on the vanes 11.

Figs. 3 and 4 represent sides and sectional elevations of one form of my improved system as applied to ship propulsion and 80 which is suitable for use on submarine vessels. In Fig. 3, the four bladed propeller is shown inside the movable casing 13 which is supported in position by the annular 85 guide 14.

90 In Fig. 4, the propeller is shown at 12 inside the casing 13, this being constructed with a boss or hub 15 on which is keyed a worm wheel 16 which may be caused to rotate by means of the worm 17 in combination with a servomotor or any other suitable mechanism. The circular guide 14 for the casing is shown in section.

95 Fig. 5 shows another form of the application of my casing when used in combination with a horizontal propeller for 100 ship propulsion. Here the paddles 21 are shown inside the permeable casing 22 which is held in position by means of the stays 23 inside a water-tight casing 24. The shaft 25 may be directly or otherwise connected with a source of power. A perforated cover-plate 26 is used to protect the space 27 between the water-tight casing 24 and the permeable casing 22, the perforations 28 in the cover-plate being necessary to give 105 free access of the water to the permeable casing.

110 Figs. 6 and 7 show side and front elevations of the permeable casing shown at 22 in Fig. 5, wherein the lateral and peripheral perforations are shown at 29 and 30 respectively.

115 Figs. 8 and 9 show side and front elevations of a casing in which the openings and vanes of the periphery are constructed in the form of buckets as shown at 31.

120 In the side view of the casing shown at Fig. 10, I have indicated a preferred form of construction making use of slots and deflecting planes or vanes in the lateral sides of the casing, the side vanes or deflectors being shown at 32.

125 Fig. 11 is a front elevation of the casing shown in Fig. 10, in which the construction 130

of the peripheral buckets is depicted at 33.

Fig. 12 shows the propelling mechanism 34 as applied to an aeroplane.

Fig. 13 shows one form of the mechanism 5 which I apply for the purpose of varying the angle of the deflecting vanes in order to control the combined lifting and propulsive thrust "C" indicated in Fig. 2. The vanes 35 are shown hinged at 36 and are 10 each connected by hinges 37 to the bent rod 38 which may be moved backward and forward by means of the lever 39 which is controlled by the handle 40 by means of the shaft and screw-thread 41.

Fig. 14 shows the paddle wheel constructed in the form of a flywheel 42 with suitable blades or vanes 43. The permeable casing is shown at 44, the whole being mounted on a suitable support or framework 45. A 20 weather vane 46 is provided to maintain the casing at the proper angle to the direction of the wind.

Fig. 15 represents a cross sectional elevation of the paddles 47 and the casing 48, the 25 water or air has free access in and out of the holes 49 in the lateral sides of the casing.

Fig. 16 represents a sectional side view of 30 a paddle wheel 47 with the casing 48 which envelops a sector of about 243 degrees of the paddle wheel, and showing the holes or perforations 49 in the lateral sides and the openings in the periphery, together with the deflecting vanes 50. The arrows indicate the direction of the rotation of the paddle 35 wheel 47 and that of the medium, water or air, in which the propeller works. It will immediately be seen from Fig. 16 how the centrifugal force of the revolving medium inside the paddle-box is utilized as in a turbine, and converted into propulsive effort. In fact, thrusts in two main directions are obtained, (1) the thrusts A. B. which are produced directly by the rotating blades in the medium in which they are submerged, 40 and (2) thrust C which is produced by the reaction of the centrifugal force by the impingement and deflections of the revolving water or air on the vanes 50 of the casing.

Figs. 17 and 18 represent respectively 50 a cross sectional elevation of the paddle and casing, and a side view of the same. In the Figs. 17 and 18 the casing covers a sector of the paddle wheel of about 210 degrees. It will immediately be seen in Fig. 18 (as in Fig. 16) that the direction of the force A with relation to the forces B. C., is in this case practically perpendicular. This disposition of the forces A. B. C. is 55 very convenient for application to an air vessel, of the "heavier than air type."

In this case the force A would be utilized principally as a lifting or sustaining force, while B. C. can be utilized as the propulsive forces of the vessel.

Figs. 19 and 20 represent respectively a side elevation of a casing and a cross sectional elevation of the same, showing another of the forms or arrangements for making the casing movable around its axis, 70 such as we have already seen in Fig. 4 of the specifications. In the case of Figs. 19 and 20 the casing is moved by means of the geared wheel 51 fixed to the casing or forming part of it, which may be rotated by 75 means of the worm or pinion 52 in combination with a handle or any other suitable mechanism.

Figs. 21 and 22 represent respectively a side elevation of the casing and a plan of 80 the same, of another form or arrangement for moving the vanes of the periphery, than that shown in Fig. 13 of the specifications. In the Figs. 21 and 22 the vanes of the periphery are constructed with an additional 85 casing or guide piece or hood 62 hinged to the permeable casing at 63. This casing 62 may be moved backward and forward by means of the screwed shaft 65 working in a nut 66 attached to the permeable casing. 90

Figs. 21 and 22 show one of the forces or arrangements for moving the lateral vanes or slats 55 which are attached to the permeable casing near the holes or openings 57 by means of the hinges 56. These slats 95 55 may be moved backward and forward by means of the toothed forked bar or shaft 58 connected with the pinion 59 and the lever 60, or other suitable mechanism.

Figs. 23 and 24 represent respectively a 100 cross sectional elevation of a vessel and a side elevation of the same showing the position of the shaft 68 of the turbine propeller 67 and its motor 69 with relation to the direction of the movement.

In this case the propellers 67 are distributed on both sides of the bottom of the vessel and their shafts work in a position parallel to the vertical plane of the said vessel.

This position of the shafts has the advantage of giving the maximum power for turning or for giving lateral movement to the vessel.

Figs. 25 and 26 represent respectively a 115 cross sectional elevation of a vessel and a side elevation of the same showing the position of the shaft 71 of a turbine propeller 70 and its motor 72 with relation to the direction of the movement. In this case the 120 propellers 70 are distributed on both sides of the vessel and their shafts 71 work in a perpendicular position to the vertical plane of the said vessel.

Fig. 27 represents a cross sectional elevation of a vessel showing the position of the shaft 74 of a turbine propeller 73 and its motor 75 with relation to the direction of the movement. In this case the propellers 73 are distributed on both side of the bilge 130

of the vessel and the shafts work in an inclined position to the vertical plane of the said vessel.

Fig. 28 represents a cross sectional elevation of a torpedo and a side elevation of the same and its motor, showing the position of the shaft 76 with relation to the direction of the movement. In this case the shaft 76 works in a perpendicular position to the vertical plane of the said torpedo.

Fig. 29 represents a side elevation of the bow of a submarine boat with a turbine propeller and movable casing fixed to the hull in a position for producing a lifting movement of the vessel. In this case the shaft 78 works in a position perpendicular to the vertical plane of the said vessel.

Figs. 30 and 31 represent respectively a cross sectional elevation of a vessel and a side elevation of the same showing the position of the shaft 80 with relation to the direction of the movement. In this case the propellers 79 are distributed on both sides of the vessel and their shafts 80 work in a perpendicular position to the vertical plane of the said vessel.

Figs. 32 and 33 represent respectively a plan of an aeroplane and a side elevation of the same with two turbine propellers 82 and 83 coupled to one shaft 84 of the motor 85 showing the position of the shaft 84 with relation to the movement. In this case the two propellers 82 and 83 are installed one on each side of the aeroplane and their common shaft works in a perpendicular position with respect to the vertical plane of the said aeroplane.

Fig. 34 represents a side elevation of a hydroplane with two pairs of turbine propellers 86 and 87 with their shafts 88 and 89 installed as we have already shown in Figs. 32 and 33 for working in a position perpendicularly to the vertical plane of the hydroplane.

Figs. 35 and 36 represent respectively a side elevation of a windmill and a front elevation of the same with its shaft 90 working in a perpendicular direction to the vertical plane of the said windmill.

The position of the shaft of the propeller with respect to the vertical plane of the vehicle or ship in which it is employed, depends essentially on the class of vessel and

the use to which it is destined. This shaft may be placed to work in any position perpendicular, parallel or inclined to the vertical plane of the ship. See Figs. 25, 26, 23, 24 and 27.

Figs. 3 and 4.—These figures have no other signification than to demonstrate graphically what is understood by "movable permeable casing." They show one of the ways in which the permeable casing may be moved around the axis of the propeller by means of the stuffing box and a handle or lever by which the mechanism is adjusted from the interior of the vessel. The details showing the roller, the flanged rim, and angle irons which fix it to the side of the vessel may be suppressed as these details have no other object than to indicate, if necessary, how a guide or suitable arrangement may be adapted to the wheel to assist in maintaining the permeable casing in position. See Figs. 19 and 20.

Treating of this matter generally I will say that as the form as well as the arrangement of the wheel, and also the permeable casing which covers it in part, and its attachment to the hull, depend on the purpose for which the propeller is to be applied, to determine the proper form of this turbine propeller and its installation, it is necessary to construct it combining the qualities of the paddle wheel and the turbine in order to obtain the greatest amount possible of the forces developed by the rotation of the blades in the medium in which they work.

I claim:

1. In a device of the class set forth, the combination with a frame, a power shaft, and a rotating wheel, comprising blades driven thereby, of a permeable casing having perforations in its lateral sides and periphery and enveloping at least one half of said rotating wheel.

2. In a marine vessel, the combination with a power shaft and a rotating wheel driven thereby, comprising blades, of a permeable casing having perforations in its lateral sides and periphery and enveloping at least one half of said rotating wheel, and deflecting vanes coöoperating with said perforations in the casing.

SALUSTIO VALDÉS CORTÉS.
